UNITED STATES PATENT OFFICE.

DANIEL C. GROVES, OF BROCKWAYVILLE, PENNSYLVANIA.

WRENCH.

No. 851,881.

Specification of Letters Patent.

Patented April 30, 1907.

Application filed January 21, 1907. Serial No. 353,314.

To all whom it may concern:

Be it known that I, DANIEL C. GROVES, a citizen of the United States, residing at Brockwayville, in the county of Jefferson 5 and State of Pennsylvania, have invented certain new and useful Improvements in Wrenches; and I do declare the following to be a full, clear, and exact description of the invention, such as will enable others skilled in the art to which it appertains to make and use the same.

This invention relates to wrenches, and has for its object to produce a device of this kind which will be strong, durable, and capable of being quickly adjusted and of retaining its adjustment after it has been set or adjusted.

The accompanying drawings illustrate the invention in which

20 Figure 1 is a longitudinal sectional view of the wrench; Fig. 2 is a top plan view of the same, a portion of the movable jaw being broken away; Fig. 3 is a transverse sectional view taken through the movable jaw; Fig. 4 25 is partly a sectional view of a portion of the adjusting mechanism.

Referring more particularly to the drawings, 1 indicates the shank or handle of my wrench which may be of any suitable size and 30 dimensions having a fixed jaw 2 at one end and the handle portion at the other. Movably mounted upon the shank is a movable jaw 3 which is provided at its upper end with a chamber 4 within which is seated a locking 35 member 5, preferably in the form of a wedge. The member 5 is adapted to be held in engagement with an incline member 6 upon the shank 1 by any suitable mechanism, preferably as a bolt or wing-nut 7. The locking 40 member 5 is held against longitudinal movement within the chamber 4 by means of guides or flanges 8 at the opposite ends of the chamber, and if desired a reinforce 9 may be secured across one side of the chambered end 45 of the jaw 3.

A buffer 10 is preferably located between the handle portion of the shank and the inclined member 6 to prevent the accidental removal of the jaw 3 and also to add strength 50 thereto. The sides of the handle are also preferably provided with the usual plates 11 and the inclined portion 6 is preferably narrower than the main portion of the shank thereby forming shoulders 12 with which the

inner ends of the guides 8 are adapted to engage and thereby causes the movable jaw to move easily without danger of binding.

Although the pressure upon the wedge member 5 will always cause it to engage with the inner end of the bolt 7, the two may be 60 connected together by recessing the opposite sides of the wedge member as shown at 13 and reducing the end of the bolt 7 so as to project through the opening in the wedge and riveting it therein, as shown at 14. 65

As above described, it will be seen that the movable jaw can be freely moved longitudinally upon the shank from one end to the other and fixedly secured thereon at any point by properly adjusting the bolt 7 so as 70 to cause the wedge member 5 to engage with the inclined face of the wedge member 6 and thereby prevent any possible movement of the jaw 3 away from the fixed jaw until after the bolt 7 has been loosened. By construct- 75 ing the parts in this manner, it will be seen that the adjustment of the wrench to its largest dimensions, as for instance, two inches, can be secured by a movement of the bolt 7 a distance equal to the height of the 80 incline, for instance less than one-half an inch, thereby permitting of the adjustment being made much quicker than the wrenches in which the movable jaw is actuated by means of a screw-thread. In opening the wrench or 85 moving the jaw 3 away from the fixed jaw, the bolt 7 can be unscrewed a sufficient distance without its moving the wedge 5 as the outward movement of the jaw will cause the wedge to move outwardly toward the bolt 90 until it comes into engagement therewith and thereby locks the jaw against further movement. In moving the jaw in the other direction, the wedge will follow the inclined surface, but if it does not, it will be forced 95 into engagement by the inward movement of the bolt. The inclined portions upon the shank will also add to its strength and by making the parts of the movable jaw of good 100 material it will have sufficient strength to withstand the great strain that is ordinarily applied to devices of this character. It is also evident that the opposing faces of the jaws may be adapted for pipe wrenches in the ordinary manner thereby making the wrench 105 a convenient tool for all purposes.

Such changes can be made in the form and construction of different parts of the wrench

as will come within the appended claims without departing from the spirit of the invention.

Having thus described my invention what I claim as new, is:—

1. An adjustable wrench having its shank provided with an inclined surface, and its movable jaw slotted and provided with guides to form a chamber and having a reinforce on one side, a wedge in the chamber and a bolt for forcing the wedge into engagement with said incline.
2. An adjustable wrench having its shank provided with an inclined surface and its movable jaw provided with a chamber, said

inclined portion being of less width than the shank, thereby forming shoulders and the walls of the chamber provided with guides at its front and rear to engage with said shoulders, a wedge in the chamber and a bolt for forcing the wedge into engagement with said inclined surface.

In testimony whereof I have hereunto set my hand in presence of two subscribing witnesses.

DANIEL C. GROVES.
